TRAIN CONTROL

Filed Oct. 15, 1923

UNITED STATES PATENT OFFICE

NED C. L. BROWN, OF SCOTTSVILLE, NEW YORK, ASSIGNOR TO GENERAL RAILWAY SIGNAL COMPANY, OF ROCHESTER, NEW YORK

TRAIN CONTROL

Application filed October 15, 1923. Serial No. 668,622.

This invention relates to automatic train control systems of the inductive type, and more particularly to systems in which alternating current is employed for transmitting control influences from the trackway to the railway vehicle.

In applying automatic train control apparatus to a train, it is found necessary to transmit control influences from the trackway to the moving train so that it may be controlled in accordance with traffic conditions ahead. On account of the speed at which trains move along the trackway at times, weather conditions and clearances, it is difficult to transmit such control influences by physically contacting devices on the train and along the trackway; and it is desirable to transmit control influences inductively through an intervening air gap to obviate this difficulty. A comparatively simple expedient for producing an influence on a moving train consists in inducing current in a coil or closed circuit carried by the train by electro-magnetic induction. In order to induce such a current in the closed circuit on the train, a change of magnetic flux is necessary; and since it is important that control influences be transmitted at extremely low speeds as well as at high speeds, it is desirable to produce such change of flux in some way other than by the movement of the vehicle alone.

In certain types of train control systems, the usual engineer's brake valve is actuated automatically to apply the brakes of the train; and in order to assure the operation of this brake valve, regardless of the failure of the source of electrical energy or of circuits, the engineer's valve is preferably constructed to assume its active position by the release of a certain force, rather than the application of such a force.

With the above and other important considerations in mind, it is proposed in accordance with the present invention to provide inductive influence communicating means which includes an inert trackway device requiring no trackway energy source, and suitable cooperating car-carried devices including an alternating current source of energy,

whereby the cooperation of these car-carried and trackway devices may cause the transmission of a control influence from the trackway to the vehicle under predetermined conditions of the trackway device regardless of the speed of the train; and to provide suitable pneumatically operated means for moving the usual engineer's brake valve to the service brake applying position in response to the release of pressure from a cylinder.

More specifically, it is proposed to provide influence communicating means in which the car-carried element has a primary winding energized by alternating current, and a secondary winding connected to a control relay, both of these circuits being tuned to resonance at the frequency of the alternating current source; and the trackway device is an inert mass of iron which disturbs the resonant constants of the circuits mentioned whereby the control relay is deenergized, the inert trackway device being provided with a coil and associated parts so constructed that under clear traffic conditions the constants of the circuits are not disturbed. It is also proposed to provide suitable influence communicating means for restoring the control relay to normal which includes a trackway transformer portion adapted to cooperate with the car-carried primary winding heretofore mentioned, and another trackway transformer portion electrically connected thereto under clear traffic conditions ahead for transmitting a control influence to a car-carried transformer portion. This method of transmitting restoring control influences is conveniently called the transformer scheme, and is especially well adapted for transmitting restoring influences, since the failure of a circuit prevents the transmission of such influence and makes the system function on the correct principle, namely, failure on the side of safety. For automatically applying the brakes, it is proposed to provide a piston in a suitable cylinder which is mechanically connected to the usual engineer's brake valve and is urged by main reservoir pressure of the usual air-brake system to the brake applying position, another and larger piston being provided which, under normal traffic

conditions, opposes the force exerted on the first piston mentioned, and by reason of its size predominates and keeps said other piston from moving the brake valve to the brake applying position under such conditions.

Other objects, purposes, and characteristic features of the invention will appear as the description thereof progresses.

In describing the invention in detail, reference is made to a single figure of the accompanying drawing, which shows in a conventional and diagrammatic manner the car-carried and trackway equipment of one embodiment of the present invention, and which illustrates the manner in which the car-carried and trackway devices are adapted to cooperate and transmit control influences distinctive in character.

29   *Trackway apparatus*

In the particular embodiment of the invention illustrated, one track of a double track railway system has been shown, the normal direction of traffic being from left to right, as indicated by the arrow. The reference character 1 designates the rails of the track which are divided by insulating joints 2 into blocks. Since the various blocks are the same, the block I and the adjacent ends of the blocks H and J only have been shown; and for convenience like parts of each block have been assigned like reference characters having distinctive exponents. Each block is provided at the exit end with the usual track battery 3 supplying energy through the usual track circuit to a track relay 4 located at the entrance end.

The train control system embodying the present invention is preferably used in conjunction with the usual wayside signals of either the color light, position light or semaphore signal type; and for convenience semaphore signals Z have been illustrated conventionally without showing their well-known control circuits and apparatus, the signal to the entrance of each block being preferably controlled by the track relay of said block and a track relay of the block next in advance, preferably indicating clear when both of these blocks are unoccupied, caution when the second block in advance only is occupied, and indicating danger when the block next in advance is occupied, all in a manner well understood by those skilled in the art.

55   Near the entrance end of each block, or rather braking distance in the rear of the exit end of each block, is a track element T adapted to initiate a suitable car-carried control relay if the next block in advance is occupied. This track element T of the block I consists of a U-shaped core of magnetic material 5, having upstanding legs terminating in enlarged pole pieces 6 and provided with a coil 7 on the back yoke thereof. This coil 35 is normally connected in a closed deenergized

circuit of low resistance by the front contact 8 of a line relay 9, which is energized through the front contact 10¹ of the track relay 4¹.

The exit end of the block I is provided with track elements TS and TP, comprising trackway secondary and trackway primary transformer portions, respectively, for transmitting restoring control influences to the vehicle. These trackway transformer portions TS and TP are substantially the same, and each comprises a U-shaped core 11 having upstanding legs terminating in enlarged pole pieces 12, the back yoke of the core 11 being surrounded by a winding 13. The windings 13 of the trackway transformer portions TS and TP located in the block I are included in a deenergized circuit passing through the front contact 14¹ of the track relay 4¹, so that said windings are connected in series when the block J next in advance is unoccupied.

Car-carried apparatus

Influence communicating and control devices.—On the locomotive or other railway vehicle is provided a car-carried element L, comprising a core 15 of general inverted U-shape and constructed of magnetic material. The legs of this core 15 terminate in pole pieces 16, adapted to cooperate with the pole pieces 6 and 12 respectively of the track elements T and TS as the railway vehicle moves along the trackway. On the legs of the core 15 of the car element L are primary coils P, which are connected in series through a suitable condenser 17 across the terminals of a suitable alternating current generator AC. The condenser 17 is preferably of such capacity that the energizing circuit for the primary coils P is in resonance when the car element L is moving between control points in a block, that is, the circuit for energizing the primary coils P is resonated, so that a maximum amount of current flow and resulting magneto-motive-force is present in the car element L while said element is not near an active track element.

On the back yoke of the core 15 of this car element L is a secondary coil S, which is connected in multiple with a condenser 18, having a condensive reactance equal to the inductive reactance of the secondary coil S for the frequency of the alternating current source AC, so that a maximum potential exists across the condenser 18 when the car element L is moving along the trackway between control points. Across the condenser 18 is connected a suitable control relay CR, in series with a suitable rectifying device A, so that the alternating current derived from the secondary winding S may be rectified and applied to the control relay CR to maintain it in its energized condition.

In the particular embodiment of the invention illustrated, this rectifying device A is of the three-element thermionic or vacuum tube

type, in which the grid 20 and the plate 21 have been connected together, and in which the filament 22 is heated by current flowing from a suitable filament battery 23. The circuit for energizing the control relay CR by unidirectional current, rectified by the rectifying device A, may be traced as follows:— Beginning at the secondary coil S, wires 24 and 25, front contact 26 of the control relay CR, wires 27 and 28, winding of the control relay CR, wire 29 to the grid 20 and plate 21 of the rectifying device A to the filament 22 of this device, through wire 30 back to the secondary winding S of the car element L.

It should be noted that this circuit includes a front contact 26 of the control relay CR, thus constituting a stick circuit for this relay, and that momentary deenergization of the control relay CR causes it to remain deenergized until otherwise restored, because the energizing circuit just traced is broken at the front contact of this relay. Since the primary windings P are energized by a circuit resonated to the frequency of the alternating current source AC, and since the secondary coil S is resonated by the condenser 18 to a potential resonance for this same frequency, a maximum potential is applied across the rectifying device A and control relay CR under normal conditions of the apparatus.

The control relay CR is constructed to act very quickly in response to a small change of current, it being of the tractive armature type in which a very light armature is used so that the inertia of moving parts only slightly retards its operation. The armature of this relay is preferably pivotally supported about its center of mass so as to make it balanced and not subject to jars and vibration, but responsive only to the flow of current through its winding. For various reasons, it is preferable to operate relays of this type by uni-directional current and the rectifying device A is employed to furnish such current. For instance, alternating current tends to cause chattering whereas pulsating direct current tends to smooth itself out into a substantially continuous direct current. Also, the flow of alternating current is much reduced by reason of the inductive reactance whereas inductive reactance does not resist the flow of uni-directional current.

If now the car element L passes over an active track element, such as the track element T when in an active condition, the resonant condition of both the primary and secondary circuits just mentioned is disturbed so that the total amount of alternating current flux passing through the secondary coil S of the car element is reduced, and the potential across the condenser 18 for each unit change of flux is reduced by reason of this non-resonant condition of the circuit including the primary coils.

This considerably smaller potential induced in the circuit including the secondary coil S in itself results in a proportional reduction in the current rectified flowing through the control relay CR, but a still further reduction in the potential across the condenser 18, and consequently across the relay CR, is produced by reason of the non-resonant condition of the circuit including the secondary coil S and the condenser 18. Since the inductive reactance of the coil S is no longer equal to the condensive reactance of the condenser 18, the current flowing through the condenser and consequently the potential across this condenser is proportionally reduced. In other words, the effect produced on the control relay CR, when the car element passes over an active track element, is equal to the effect produced by reason of the non-resonant condition of the primary winding, modified by the effect produced by the non-resonant condition of the secondary coil and its associated condenser, so that the ultimate effect produced is equal to the product of the separate effects produced as a result of bringing the primary and the secondary circuit out of resonance. It is this multiplied effect that causes a very pronounced change in the current flowing in the control relay CR; and since this relay is of the quick acting, uni-directional current, tractive armature type in which the armature is extremely light, a momentary reduction only of current in the control relay is necessary to cause its operation. This reduction in the energizing current for the control relay CR causes it to open its front or stick contact 26, thereby maintaining deenergization of this relay by reason of complete interruption of its energizing circuit.

In order to again automatically restore the control relay CR, a suitable restoring or reset relay RR is provided. This reset relay RR is at times energized in response to a control influence received by the car-carried transformer portion LS located to cooperate with the trackway transformer portion TP. This car-carried transformer portion LS consists of an inverted U-shaped core 35 terminating in enlarged pole pieces 36, and having windings 37 provided on each of the legs of this core 35. These windings 37 are connected in series across the reset relay RR through a condenser 38. The condenser 38 preferably has a capacity so that the condensive reactance of this condenser is substantially equal to the sum of the inductive reactances of the car element LS and the reset relay RR for the frequency of the alternating current source AC, so that the restriction to the flow of current through the reset relay RR is reduced to a minimum.

If the control relay CR is deenergized for any reason, possibly because the car element L has passed over a track element T in its

active condition, this relay may again be restored by the momentary energization of the reset relay RR as the train is about to pass out of a certain block when the next block in advance is unoccupied. As the car element L passes over the trackway transformer portion TS, an alternating current is induced in the winding 13 of this element TS, thereby causing alternating current to flow in the winding 13 of the other trackway transformer portion TP, so that an alternating current magneto-motive-force is set up in the core 11 of the transformer portion TP. Since the car-carried transformer portion LS is in inductive relation with the transformer portion TP at the instant the car element L passes over the transformer portion TS, a similar alternating current flux is set up in the car-carried transformer portion LS, thereby inducing a voltage in the windings 37 which, by reason of the resonant condition of the circuit including the reset relay RR, causes sufficient current to flow to energize this reset relay RR. This reset relay RR is preferably slow dropping, so that its front contact 39 is closed for a considerable period of time.

As the car-carried elements L and LS recede from the trackway transformer portions TS and TP, sufficient voltage is again impressed upon the condenser 18 to energize the control relay CR through the following circuit:—Beginning at the secondary winding S of the car element L, wires 24 and 40, front contact 39 of the reset relay RR, wires 41 and 28, winding of the control relay CR, wire 29, through the rectifying device A, wire 30 back to the secondary winding S of the car element L. The momentary completion of this circuit causes the control relay CR to assume its energized position, thereby again completing the stick circuit heretofore traced and restoring the control relay CR to its normal condition.

Speed restricting apparatus.—Although the control relay CR may be used to control the train in a caution block in any suitable manner, it is proposed to employ this control relay CR for controlling the operation of a suitable speed control apparatus or speed restricting device; and a speed restricting device of the cyclic type which provides a restriction in the speed in accordance with the movement of the train along the trackway has been conventionally illustrated. The apparatus or device conventionally shown comprises a centrifugal speed-responsive device or governor G, including a shaft 45 journaled in projecting bosses 46 and 47 and driven by the wheels and axle of the rail-way vehicle in any suitable manner, as by transmission gearing. To the shaft 45 is pinned a collar 48 having projecting ears to which are pivotally secured links 49. The free ends of the links 49 are pivotally connected to similar links 50, having their other

ends connected to ears projecting from a sleeve 51 slidably mounted on the shaft 45. At the junction point of the links 45 and 50 are provided weights 52, corresponding to the centrifugal weights of the well known fly-ball governor. These weights 52 tend to assume a position remote from the shaft 45 in response to centrifugal force as the shaft 45 is rotated. This force tends to cause the slideable collar 51 to move upward on the shaft 45 in opposition to the force exerted by the coil spring 53 surrounding this shaft. The slideable collar 51 is provided with a peripheral groove which is engaged by the bifurcated end of a floating lever 54, the other end of this floating lever 54 being provided with a roller 55 riding on the edge of a cam K. A hook 56 is pivotally secured to the floating lever 54 at an intermediate point, and is urged downwardly by a spring 57, having its free end anchored to a pin 58. The hook 56 terminates in a piece of insulation 59 adapted to engage a spring contact finger 60, if the hook 56 assumes a predetermined elevated position.

The cam K, on which the roller 55 heretofore mentioned rides, normally assumes the position with this roller 55 in its lowermost position as shown, thereby allowing the governor G to rotate at a comparatively high speed before the insulation 59 raises the contact 60. This cam K is firmly secured to a shaft 61 pivoted in journals 62 and 63. The shaft 61 is provided with a worm gear 64, having a milled portion 65. To the shaft 61 is pinned a collar 66, having a projecting arm 67 urged in a predetermined position by the coil spring 68, and having its other end secured to an anchoring pin 69. It is thus seen that the spring 68 acts to urge the cam K to its normal position as shown in the drawing.

To the governor shaft 45 is pinned a bevel gear 75, which meshes with a bevel gear 76 pinned to a shaft 77 pivotally secured by the journal 78. A shaft 79 is operatively connected to the shaft 77 by a universal joint 80, so that this shaft may be rotated by the shaft 77 regardless of the exact alignment of these two shafts. The free end of the shaft 79 fits loosely in a sleeve 81 fastened to the core 82 of a cam starting magnet CS, having a winding 83. On the shaft 79 and near the free end thereof is provided a worm 84 adapted to engage the worm wheel 64 when the cam starting magnet CS is deenergized. Under normal clear traffic conditions of the car-carried apparatus, that is, when the control relay CR is energized, the cam starting magnet CS is energized through a circuit including the battery 85 and the front contact 39 of the control relay CR, which may be readily traced in the drawing.

It will be noted that deenergization of the control relay CR causes the cam starting

magnet CS to assume its deenergized position, thereby mechanically coupling the governor shaft 45 driven by the wheels of the vehicle to the cam K. As the train moves 5 along the trackway, the cam K is gradually rotated in one direction or the other depending upon whether the train is moving pilot or tender first, thereby gradually moving the roller 55 upwardly, thus causing the insulation 59 to move toward the contact 60. It is thus seen that the speed which the vehicle may assume, without causing the insulation 59 to open the contact 60, must be gradually reduced as the roller 55 assumes higher positions in response to the movement of the cam K driven by the worm 84.

When the vehicle has moved a predetermined distance along the trackway after the cam starting magnet CS has been deenergized, the worm 84 reaches the mutilated portion of the worm wheel 64 so that no further rotation of the worm wheel 64 takes place regardless of the continued rotation of the worm 84. This construction is provided so 25 that the ultimate speed limit enforced by the particular cam K will continue until the cam starting magnet CS is again energized.

Brake applying mechanism.—In the embodiment of the invention illustrated, suitable means for causing an automatic brake application have been provided, which is made effective when the contact 60 is opened as a result of excessive speed; that is, actual speed manifested by the governor G as compared with the permissive speed set up by the position of the cam K, as heretofore described. As shown, the brake applying apparatus includes an electro-pneumatic valve EPV having a winding 90 which is energized 35 by a circuit including the contact 60 and a suitable source of energy such as a battery 91. This electro-pneumatic valve EPV comprises a chamber having partitions 92 and 93 dividing the chamber into compartments 94, 40 95 and 96. These partitions 92 and 93 are provided with valve seats adapted to accommodate valves 97 and 98 secured to the valve stem 99, having its upper end guided in the plug 100 and having its lower end secured 45 to an armature 102 disposed in the magnetic shell 103 of this electro-pneumatic valve EPV, the shell 103 being closed at its lower end by a non-magnetic cap 104. On the valve stem 99 is a collar 108, between which and the 50 partition 93 is interposed a compression coil spring 109.

The electro-pneumatic valve EPV just described is adapted to control a brake valve actuator attached to the valve casing of the usual engineer's brake valve as illustrated. The particular engineer's brake valve shown 60 is of the engine and tender or E. T. type, and is provided with a valve and seat having the necessary ports to provide a release, running, holding, lap, service and emergency

position as shown by the various notches. This engineer's brake valve E includes a valve stem 110, to which is secured the usual brake valve handle 111 and a projecting arm 112. Directly below the handle 111 and loose 70 on the valve stem 110 is a pinion 113 meshing with a rack 114, which has its ends secured to a large piston 115 and a small piston 116, respectively. These pistons 115 and 116 are provided with the usual rings or packings 75 and fit in cylinders 117 and 118 which are integral with and form part of a housing 119 secured to the top of the usual engineer's brake valve casing. The pinion 113 has therein an upstanding pin 120, which is adapted to engage the arm 112 projecting from the valve stem 110 after a predetermined arc of movement of the pinion 113 from its normal position. Thus, if the pinion 113 is rotated in a counter-clockwise direction as shown, a certain amount of lost motion will take place before the pin 120 engages the arm 112 to operate the valve handle and cause an automatic application of the brakes. This lost motion is provided so that the engineer may move the handle 111 to the release position 85 under normal conditions of the brake valve actuating mechanism without causing engagement of the arm 112 and the pin 120.

The small cylinder 118 is provided with a pipe 124 directly and permanently connected to main reservoir or other source of air pressure, so that air pressure of a predetermined amount is always present in this cylinder 118. The upper compartment 94 of the EPV is 90 connected to main reservoir pressure by the pipe 125; the lower compartment 96 is in communication with atmospheric pressure through the port 126; and the middle compartment is connected to the large cylinder 117 of the brake valve actuator by the pipe 127.

With the electro-pneumatic valve EPV in its normal energized condition, main reservoir pressure may pass from the compartment 94 into the compartment 95 and through the pipe 127 into the large cylinder 117. Since the pressures in the cylinders 117 and 118 are the same, and since the cylinder 117 is larger than the cylinder 118, the force exerted on the piston 115 predominates over the force exerted on the piston 116, thereby maintaining the rack 114 in its extreme righthand position, as shown.

If now the circuit for energizing the winding 90 of the EPV is interrupted because the speed limit as set up by the cam K has been exceeded, the valve 97 is closed and the valve 98 is opened, so that the compartment 95 is 110 connected to atmosphere through the compartment 96, thus releasing the pressure from the cylinder 117 and causing the rack 114 to move toward the left by reason of main reservoir pressure in the cylinder 118. This differential action of the pistons 115 and 116 115

is deemed to be extremely reliable, in that the force necessary to operate the engineer's valve to the brake applying position is derived by main reservoir pressure which must necessarily be present when the locomotive or other railway vehicle and the train control apparatus therefor is in use. In other words, in the particular brake valve actuator shown, a certain force which can be relied upon is always present tending to cause an automatic brake application, and another and predominating force is used to maintain the brake valve actuator in its normal inactive position, so that all that is necessary to cause an automatic brake application is the release of this latter force which may be readily and reliably effected.

Operation

Let us assume that the car-carried apparatus illustrated in the drawing is in its normal or clear traffic condition as shown, and that the car or locomotive is moving in the block H, while the block J is occupied. As the train proceeds through the block H, the car-carried elements L and LS come into communicating relation with the trackway transformer portions TS^o and TP^o without producing any action on the car outside of the momentary energization of the reset relay RR. As the train moves into the block I, which is a caution block because the block J is occupied by another train, a certain restriction in the movement of the train through this block is required.

With the block J occupied by another train as just assumed, the track relay 4¹ is deenergized, thus deenergizing the line relay 9 and opening the circuit for the track element T. As the car element L passes by the track element T, the momentary cooperation of the core 5 with the core 15 through a small intervening air gap causes the inductive reactance of the primary winding P and the secondary winding S of the car element L to change momentarily. This momentary change in the inductive reactance of the primary and secondary windings disturbs the resonant condition of the exciting circuit for the primary coil, and also the energizing circuit for the control relay CR, so that the maximum amount of flux passing through the car element L as well as the potential impressed across the condenser 18 for each unit change of this magnetic flux is appreciably reduced, thereby effecting an enormous reduction in the flow of current through the control relay CR, causing it to drop its front contact 26 and break its energizing stick circuit. With the control relay CR deenergized, the opening of its front contact 86 causes deenergization of the cam-starting magnet CS and allows the worm 84 to operatively engage the worm wheel 64.

As the train proceeds through the block I,

the gradual rotation of the cam K, by reason of the engagement of the worm 84 with the worm wheel 64, causes a gradually restricting speed limit to be set up by the changing position of the roller 55 of the floating lever 54. The shape of the cam K is preferably such that the permissive speed thus set up assures stopping of the train before reaching the end of a block. Since the braking distance of a particular train in different blocks varies with the grade and the like, and since this distance varies for different trains on account of the length of the train, conditions of the brake shoes, loading of the various cars, and the like, it is considered desirable to cut the cam K to restrict the train to a certain arbitrary value found suitable for the various conditions encountered in practice. The cam K is preferably so cut that a minimum speed limit of, say, 15 miles per hour, is established when it reaches its ultimate position, so that the train may continue to run at this low speed limit after passing the end of a caution block.

Let us assume that the train has passed through the block I and has reduced its speed below the permissive speed set up by the cam K, and that said another train has moved entirely out of the block J before the train in question reaches the trackway transformer portions TS and TP. With the block J again unoccupied and the track relay 4¹ energized, the front contact 14¹ is closed and the coils 13 are again in a closed circuit. As the car elements L and LS simultaneously come into cooperation with the trackway transformer portions TS and TP, an alternating current is induced in the trackway circuit including the coils 13 by reason of the alternating flux emanating from the pole pieces 16 of the car element L. This current flowing in the coils 13 of the trackway transformer portion TP sets up an alternating magnetic flux in the car-carried transformer portion LS, thereby inducing a current in the resonated circuit of the reset relay RR, causing it to pick up its front contact 39.

As these car elements L and LS recede from the trackway transformer portions TS and TP, a resonated condition of circuits including the primary coil P and the secondary coil S again take place; and since the reset relay RR is slow dropping, the control relay CR is again picked up through the pick-up circuit including the front contact 39 of the reset relay RR. After this control relay CR is once picked up, the pick-up circuit heretofore traced is again completed, thus permanently maintaining this control relay CR energized.

Had the block J still been occupied by said another train when the car in question reached the trackway transformer portions TS and TP, no resetting control influence would have been transmitted, because the cir-

cuit connecting the coils 13 would have been open under this condition, and the train in question would have been compelled to pass through the block J at the minimum speed restriction heretofore mentioned with the cam K in its ultimate position:

Let us assume now that the train in question is passing into the block I under clear traffic conditions of the apparatus with the block J next in advance unoccupied. Under this condition of the trackway apparatus, the coil of track-element T is closed in a suitable circuit including the front contact 8 of the line relay 9. As the car element L passes over the track element T, a current is set up in the coil 7 of this track element T which opposes the passage of flux from the car element L through the core of the track element T to a large extent, so that the inductive reactance of the primary coil P and the secondary coil S of the car element L is only slightly changed, whereby the resonant condition of the circuits including these coils is not appreciably disturbed and the current energizing 25 the control relay CR is not sufficiently reduced to cause this relay to be deenergized. In other words, the closure of the coil 7 in a suitable circuit of low resistance, which may include either inductive or condensive reactance, causes this core 5 to lose its inherent inductive qualities, so that the self-induction of the car element L is not materially changed as it passes over this track element under clear traffic conditions ahead.

Having thus shown and described one specific embodiment of the present invention, it is desired to be understood that the specific embodiment shown and described has been chosen for illustrative purposes, rather than 35 to show the scope of this invention. For instance, the present invention may be used in connection with any type of speed restricting apparatus in which a certain initiating control is effected when entering caution territory, and a suitable restoring control is effected when entering a clear block; and it is desired to be understood that various other changes and modifications may be made to adapt the invention to the various railway 45 systems encountered in practice without departing from the scope or the idea of means underlying the present invention.

What is desired to be secured by Letters Patent of the United States, is:—

1. Influence communicating means for automatic train control systems comprising, a car-carried core of magnetic material having a primary and a secondary coil thereon, a source of alternating current on the car for energizing said primary coil, a condenser connected in series with said primary coil, a condenser connected in multiple with said secondary coil, an electro-responsive device connected in multiple with said last mentioned condenser, and traffic controlled means

along the trackway for magnetically bridging said core under predetermined traffic conditions ahead.

2. Influence communicating means for automatic train control systems comprising, a car-carried core of magnetic material having a primary and a secondary coil thereon, a source of alternating current of a predetermined frequency for energizing said primary coil, means for resonating the circuit for said primary coil to the frequency of said source, an electro-responsive device connected to said secondary coil, means for resonating the circuit including said secondary coil and said electro-responsive device to the frequency of said source, and trackway means positioned in direct inductive relation to the car-carried core, for disturbing the resonant condition of said primary and secondary circuits when the car-carried core passes thereby.

3. Car-carried apparatus for automatic train control systems comprising; a car-carried speed restricting device of the type in which a cam is at times driven from the wheels of the vehicle which sets up gradually decreasing speed limits when so driven and which effects an automatic brake application if the actual speed of the vehicle exceeds the permissive speed; means for initiating said speed restricting device including a resonated alternating current circuit including a control relay; and means for restoring said device including means for transmitting a control influence to a trackway circuit through an intervening air gap, and means to transmit a control influence from the trackway back to the car through another intervening air gap.

4. Car-carried apparatus for automatic train control systems comprising; a car-carried speed restricting device which sets up gradually decreasing speed limits when initiated and which causes an automatic brake application if the actual speed of the vehicle exceeds the permissive speed; means for initiating said speed restricting device including a resonated coil and a control relay; means for restoring said speed restricting device including a core of magnetic material having a winding thereon, a reset relay connected to said winding, and means for resonating the circuit including said reset relay and said winding.

5. Car-carried apparatus for automatic train control systems comprising; a car-carried speed restricting device which sets up gradually decreasing speed limits when initiated and which causes an automatic brake application if the actual speed of the vehicle exceeds the permissive speed; means for initiating said speed restricting device comprising two resonated circuits, one of which is directly connected to a source of alternating current of the frequency for which these circuits are resonated, and a control relay nor-

mally connected in a stick circuit; and means for restoring said device comprising a reset relay having a front contact in multiple with the stick contact of said control relay, an influence receiving coil connected in the circuit with said reset relay, and means for resonating the circuit for said reset relay to the frequency of said alternating current source.

6. Influence communicating means for automatic train control systems comprising two car-carried electrically insulated circuits resonated to a predetermined frequency, and a single element located at each of a plurality of control points along the trackway, positioned in direct inductive relation to said circuits, and controlled in accordance with traffic conditions ahead simultaneously directly affecting both of said circuits upon passage of the car-carried circuits by such control points and thereby simultaneously changing the resonant condition of both of said circuits.

7. Influence communicating means for automatic train control systems of the intermittent inductive type comprising, a car-carried core having a primary coil and a secondary coil thereon, a source of alternating current for energizing said primary coil, a relay connected in series with said secondary coil in a circuit including a front contact of said relay, said relay being maintained energized by energy derived from said source through the inductive coupling including said core, means for resonating the circuit including said primary coil at the frequency of said source, means for resonating the circuit including said secondary coil and said relay at the frequency of said source, and traffic controlled trackway means which when in its active stopping condition magnetically cooperates with both said primary and said secondary coil to disturb the resonant condition of both of said coils upon passage of said core by said trackway means, whereby the current flowing in said relay decreases to a value to allow said relay to assume its de-energized position and thereby interrupt the energizing circuit of said relay.

8. Influence communicating means for automatic train control systems, comprising the combination of a car-carried influence receiving element including a laminated core located so as to be in inductive relation with the trackway, a coil on said core, a control relay having a front contact, a circuit including said coil, the winding of said relay and said contact in series, a source of alternating current for energizing said circuit, means for resonating said coil at the frequency of said source, rectifying means in said circuit for allowing the flow of uni-directional current only through the winding of said relay, and of trackway means which when in its active condition disturbs the resonant condition of said coil upon passage of said coil by said

trackway means, whereby said relay is caused to assume its de-energized position when the car passes an active trackway device.

9. A train control system of the intermittent inductive type comprising vehicle carried apparatus including a core having a primary coil and a secondary coil thereon, a circuit for energizing said primary coil including an alternating current source of supply, a stick relay, a secondary circuit including the secondary winding, the winding and a front contact of said stick relay, means for resonating said primary circuit to a predetermined frequency, means for resonating said secondary circuit to the same frequency, and trackway means for disturbing the resonant condition of both of said circuits upon passage of the vehicle thereby, said trackway means including an iron core having a winding thereon which winding is open circuited under unfavorable traffic conditions.

10. The combination with a track and a vehicle moving thereon, of a brake system including an engineer's valve having manual movement to extreme positions, and means located along the track and upon the vehicle for placing the engineer's valve in an intermediate position and at the same time effecting a reduction of pressure in the brake system, said means being ineffective to place said valve in any other position and including differential area piston mechanism constructed so that it is actuated if pressure is released therefrom and is restored to normal after such pressure is reapplied.

11. In inductive influence communicating apparatus for automatic train control systems of the intermittent inductive type, the combination with a vehicle carried core having a primary and a secondary winding thereon, a primary circuit including the said primary winding and a source of alternating current, a secondary circuit including the secondary winding, a winding and a front contact of a stick relay, means for resonating said primary circuit to a certain frequency, means for resonating said secondary circuit to the same frequency, and trackway means located in inductive relation with said core upon passage of the vehicle by said trackway means.

12. Car-carried apparatus for automatic train control systems of the intermittent inductive type comprising, a core having a primary coil and a secondary coil thereon, another core having an inducing coil thereon, a stick relay having a front contact, a source of alternating current, a restoring relay, a circuit for said primary coil including said alternating current source and tuned to the frequency of said source, a circuit for said secondary coil including the winding of said stick relay and its front contact in series also tuned to the frequency of said source, and a circuit for said inducing coil including said restoring relay and also tuned to the fre-

quency of said source, and a pick-up circuit for said stick relay including a front contact of said restoring relay.

13. In a train control system of the intermittent inductive type, the combination with car-carried apparatus including; a core having a primary coil and a secondary coil thereon, another core having an inducing coil thereon, a stick relay having a front contact, 5 a source of alternating current, a restoring relay, a circuit for said primary coil including said alternating current source and tuned to the frequency of said source, a circuit for said secondary coil including the winding of 10 said stick relay and its front contact in series also tuned to the frequency of said source, a circuit for said inducing coil including said restoring relay and also tuned to the frequency of said source, and a pick- 15 up circuit for said stick relay including a front contact of said restoring relay; of trackway apparatus including a track element consisting of an inert magnetic body when in its active condition for disturbing the 20 resonated condition of said primary and said secondary circuits under danger traffic conditions, and means for electro-magnetically coupling said primary coil to said inducing coil under clear traffic conditions. 25
14. In a train control system of the intermittent inductive type, the combination with car-carried apparatus including; a core having a primary coil and a secondary coil thereon, another core having an inducing coil 30 thereon, a stick relay having a front contact, a source of alternating current, a restoring relay, a circuit for said primary coil including said alternating current source and tuned to the frequency of said source, a circuit for 35 said secondary coil including the winding of said stick relay and its front contact in series also tuned to the frequency of said source, a circuit for said inducing coil including said restoring relay and also tuned to the frequency of said source, and a pick-up circuit 40 for said stick relay including a front contact of said restoring relay; of trackway apparatus including a track element consisting of an inert magnetic body when in its active condition for disturbing the resonated condition of said primary and said secondary 45 circuits under danger traffic conditions, and other trackway means for inducing a current in said inducing coil to pick-up restoring relay effective under clear traffic conditions. 50

15. Influence communicating means for automatic train control systems comprising, a car-carried core of magnetic material having a primary and a secondary coil thereon, a 55 source of alternating current of a predetermined frequency for energizing said primary coil, means for resonating the circuit for said primary coil to the frequency of said source, a stick electro-responsive device connected to said secondary coil, means for resonating the

circuit including said secondary coil and said electro-responsive device to the same frequency, trackway means for disturbing the resonant condition of said primary and said secondary circuits when the car-carried core passes thereby, and thereby causing said electro-responsive device to be de-energized, and means for restoring said electro-responsive device to normal. 70

16. Influence communicating means for automatic train control systems comprising, a car-carried core of magnetic material having a primary and a secondary coil thereon, a source of alternating current of a predetermined frequency for energizing said primary coil, means for resonating the primary circuit including said primary coil to the frequency of said source, a stick electro-responsive device connected to said secondary coil, means for resonating the secondary circuit including said secondary coil and said electro-responsive device to the same frequency, trackway means for disturbing the resonant condition of said primary and said secondary circuits when the car-carried core passes thereby and thereby causing said electro-responsive device to be deenergized, and means controlled from the trackway through an intervening air gap for restoring said electro-responsive device to normal. 75

17. Influences communicating means for automatic train control systems comprising, a car-carried core of magnetic material having a primary and a secondary coil thereon, a source of alternating current of a predetermined frequency for energizing said primary coil, means for resonating the primary circuit including said primary coil to the frequency of said source, a stick electro-responsive device connected to said secondary coil, means for resonating the secondary circuit including said secondary coil and said electro-responsive device to the same frequency, trackway means for disturbing the resonant condition of said primary and said secondary circuits when the car-carried core passes thereby and thereby causing said electro-responsive device to be de-energized, and a restoring relay having a front contact which if closed restores said electro-responsive device to normal, and means located at control points along the trackway and effective under clear traffic conditions for causing the flow of a current in the winding of said restoring relay upon passage of the vehicle by such control point. 100

18. Influence communicating means for automatic train control systems comprising, two car-carried electrically insulated circuits resonated to a predetermined frequency, and means at each of a plurality of control points along the trackway each including a soft iron core for simultaneously magnetically linking both of said circuits upon passage of a vehicle by a control point, and thereby 125

simultaneously changing the resonant condition of both of said circuits to detune such circuits.

19. Influence communicating means for automatic train control systems comprising, 5 a car-carried element of magnetic material having a primary and a secondary coil thereon, a source of alternating current on the car for energizing said primary coil, a condenser connected in series with said primary coil, a 10 condenser connected with said secondary coil, said condensers tuning the circuits of the two coils for the frequencies of said current source, an electro-responsive device connected to the secondary coil and traffic controlled 15 means along the trackway for magnetically bridging said element under predetermined traffic conditions ahead to cause initiation of said electro-responsive device by detuning 20 said circuits.

20. Influence communicating means for automatic train control systems comprising, car-carried inductively related primary and secondary coils, a source of alternating current of a predetermined frequency for energizing said primary coil, means for resonating the circuit for said primary coil to the frequency of said source, an electro-responsive device connected to said secondary coil, 25 means for resonating the circuit including said secondary coil and said electro-responsive device to the frequency of said source, and trackway means for disturbing the resonant condition of said primary and secondary circuits when the car-carried coils pass thereby to thus detune said circuits and 30 initiate said electro-responsive device.

21. Influence communicating means for automatic train control systems comprising a 40 car-carried magnetizable core, a primary and a secondary coil on said core, two electrically insulated circuits each including one of said coils, a source of alternating current for energizing the circuit including the primary coil, 45 said circuits being resonated to the frequency of said source, a relay in the other circuit normally energized by current derived from flux emitted by said primary coil, and means located along the trackway which under dangerous traffic conditions ahead disturbs the 50 resonant condition of said circuits by bridging the core when said core moves by said trackway means whereby to decrease the current in the secondary circuit so as to de-energize said relay.

22. Influence communicating means for automatic train control systems comprising, two car-carried coils located in inductive relation with the trackway, two electrically insulated circuits each including one of said coils, a relay connected in one of said circuits, a source of alternating current connected only in the other circuit, said circuits being resonated to the frequency of said 65 source of alternating current, and means lo-

cated at points along the trackway which under dangerous traffic conditions ahead simultaneously detunes both of said circuits by magnetically cooperating with said coils, the various constants being so selected that said relay will assume its de-energized position when the resonance of the two circuits is disturbed by reason of the co-operation of said car-carried coil and the means located along the trackway.

23. Influence communicating means for automatic train control systems of the intermittent inductive type comprising, a car-carried primary coil and secondary coil, a source of alternating current for energizing 80 said primary coil, a relay connected in series with said secondary coil in a circuit including a front contact of said relay, said relay being maintained energized by energy derived from said source through inductive coupling, 85 means for resonating the circuit including said primary coil at the frequency of said source, means for resonating the circuit including said secondary coil and said relay at the frequency of said source, and traffic 90 controlled trackway means which when in its active stopping condition magnetically cooperates with both said primary and said secondary coil to disturb the resonant condition of both of said coils upon passage by said trackway means, whereby the current flowing in said relay decreases.

24. A train control system of the intermittent inductive type comprising vehicle carried apparatus including a primary coil and a secondary coil, a circuit for energizing said primary coil including an alternating current source of supply, a stick relay, a secondary circuit including the secondary winding, the winding and a front contact of said stick relay, means for resonating said primary circuit to a predetermined frequency, means for resonating said secondary circuit to the same frequency, and trackway means for disturbing the resonant condition of both of said circuits upon passage of the vehicle thereby, said trackway means including an iron core having a winding thereon which winding is open circuited under unfavorable traffic conditions.

25. In inductive influence communicating apparatus for automatic train control systems of the intermittent inductive type, the combination with a vehicle carried primary and secondary winding, a primary circuit including the said primary winding and a source of alternating current, a secondary circuit including the secondary winding and a winding of a stick relay, means for resonating said primary circuit to a certain frequency, means for resonating said secondary circuit to the same frequency, and trackway means located in inductive relation with said windings upon passage of the vehicle by said trackway means.

26. Influence communicating means for automatic-train control systems comprising, a car-carried primary and secondary coil, a source of alternating current of a predetermined frequency for energizing said primary coil, means for resonating the circuit for said primary coil to the frequency of said source, a stick electro-responsive device connected to said secondary coil, means for resonating the circuit including said secondary coil and said electro-responsive device to the same frequency, trackway means for disturbing the resonant condition of said primary and said secondary circuits when the car-carried coils pass thereby, to thereby cause said electro-responsive device to be de-energized, and means for restoring said electro-responsive device to normal.

27. The combination with a track and a vehicle moving thereon, of a brake system including an engineer's valve having manual movement to extreme positions, and means located along the track and upon the vehicle for placing the engineer's valve in an intermediate position and at the same time effecting a reduction of pressure in the brake system, said means being ineffective to place said valve in any other position and including a differential piston normally having equal unit pressures on its two ends.

28. A combined manual and automatic brake applying device comprising; an engineer's brake valve having a brake pipe charging position and a non-charging position; a member normally assuming a position permitting said brake valve to assume any of its positions in response to manual operation; and means for forcibly operating said member to cause said brake valve to be moved to a non-charging position consisting of differential area fluid pressure responsive means which responds to fluid pressure acting on the smaller area after fluid pressure is vented from the larger area and which means restores said member to normal when fluid pressure is reapplied to the large area, and an electrically operated valve controlled by suitable train control means for venting fluid pressure from the larger area when the brakes are to be automatically applied.

29. A combined manual and automatic brake applying device comprising; an engineer's brake valve having a brake pipe charging position and a non-charging position; a member normally assuming a position permitting said brake valve to assume any of its positions; and means for forcibly operating said member to cause said brake valve to be moved to a non-charging position consisting of differential area fluid pressure responsive means, which respond to fluid pressure acting on the smaller area after fluid pressure is vented from the larger area and which means restores said member to normal when fluid pressure is reapplied to the larger

area, and an electrically operated three-way valve controlled by suitable train control means for normally applying fluid pressure to the larger area from a suitable fluid pressure source and for venting fluid pressure from said larger area when an automatic brake application is to take place.

30. A brake valve actuator for operating an engineer's brake valve from a normal brake pipe charging position to an abnormal non-charging position comprising, differential piston means including two pistons of different areas having fluid pressure derived from the same source normally acting thereon and acting in such a manner that the forces of the two pistons oppose each other and the force of the larger piston predominates and operates the actuator to and retains the actuator in the normal position, and means for venting fluid pressure from the larger piston to allow the force exerted upon the smaller piston to move the engineer's brake valve to the non-charging position when the engineer's brake valve is to be automatically operated.

31. In a train control system, the combination with an engineer's brake valve having a brake pipe charging position and a non-charging position, a member normally assuming a position permitting said brake valve to assume any of its positions in response to manual operation, means for forcibly operating said member to cause said brake valve to be moved to a non-charging position consisting of differential area fluid pressure responsive means, the response of which is due to fluid pressure acting on the smaller area upon fluid pressure being vented from the larger area and which means restores said member to normal when the source of fluid pressure is reapplied to said larger area; and a normally energized electro-pneumatic valve for normally supplying fluid pressure against the larger area and which if de-energized vents the fluid pressure from the said larger area.

32. Influence communicating means for automatic train control systems, comprising, a car-carried magnetizable core terminating in two depending legs, a primary and a secondary coil on said core, two electrically insulated circuits each including one of said coils, a source of alternating current for energizing the circuit including the primary coil, each of said circuits being resonated to the frequency of said source, a relay in the other circuit normally energized by current caused by flux emitted by said primary coil and means located along the trackway which, under dangerous traffic conditions ahead, disturbs the resonant condition of said circuits by magnetically bridging said legs when said core moves past said trackway means, whereby to drop said relay.

33. In an inductive train control system,

a car-carried core having a primary and a secondary coil thereon, a circuit for the primary coil including an alternating current source, a circuit for the secondary coil including a translating device, means tuning each of said circuits to the frequency of said source, a track element in inductive relation to said core and consisting of an inert magnetic body for decreasing the magnetic reluctance of the circuit through the car-carried core to thus detune the car circuits and initiate said translating device.

34. In an inductive train control system, a car-carried core having a primary and a secondary coil thereon, a circuit for the primary coil including an alternating current source, a circuit for the secondary coil including a translating device, means tuning each of said circuits to the frequency of said source, a track element in inductive relation to said core and consisting of an inert magnetic body for decreasing the magnetic reluctance of the circuit through the car-carried core to thus detune the car circuits and initiate said translating device, a choke coil on the track element, and traffic controlled means for opening and closing a low resistance circuit including the choke coil.

In testimony whereof I hereby affix my
30 signature.
